SPARK PLUG INSULATOR

Filed May 31, 1927

INVENTOR.
EDWARD E. HUNTINGTON
BY *Chester H. Braselton*
ATTORNEY.

UNITED STATES PATENT OFFICE

EDWARD E. HUNTINGTON, OF TOLEDO, OHIO, ASSIGNOR TO THE WILLYS-OVERLAND COMPANY, OF TOLEDO, OHIO, A CORPORATION OF OHIO

SPARK-PLUG INSULATOR

Application filed May 31, 1927. Serial No. 195,247.

My invention relates to the ignition system of internal combustion engines and it has particular relation to engines wherein the spark plugs are mounted in a deep seated 5 position, such for example, as in the so-called Knight engines.

One of the principal objects of my invention is to overcome non-firing and miss-firing of internal combustion engines of the above 10 designated class.

Another object of my invention is to provide an ignition system for Knight engines having a high potential secondary circuit which will give regular uninterrupted 15 performance.

It is a further object of my invention to provide a spark plug construction for engines having deep seated apertures to receive the plug, which obviates "missing".

20 It is a further object of my invention to provide a modified spark plug construction for Knight engines having a small bore which is capable of operating regularly, at high engine pressures and under adverse atmospheric conditions.

Internal combustion engines, particularly those of the Knight class, include a well portion, wherein the spark plug is mounted. It has been observed that under certain conditions engines of this class function irregularly, that is one or more of the cylinders fails to perform, resulting in what is commonly known as "missing". This phenomenon is observed under various operating conditions and is aggravated by moist weather conditions, excessive internal pressures, rich gas mixtures, old spark plugs and perhaps other factors. It has been noted that contrary to expectation, the more powerful the 40 ignition system the more apparent is this "missing" phenomena, and excepting for this fact, the more powerful ignition systems are to be desired.

According to my invention I have provided 45 an insulating medium surrounding the head of the spark plug together with the connecting wire thereby eliminating these undesirable operating characteristics.

A better understanding of the invention 50 may be had by referring to the drawing

which is a sectional view of the upper portion of a Knight engine and illustrates an embodiment of my invention which may be preferred.

The drawing illustrates but a portion of a 55 cylinder casting or block 10 showing its relation to a cylinder head 11 including a spark plug well 12 formed in the central portion of the head. It is made secure to the block 10 by means of a plurality of bolts 60 and includes a compression ring 13 and sealing ring 14 which engage the inner of two reciprocating sleeves 16 and 17. A cover plate 18 extends over the major portion of the cylinder head and is retained in sealed 65 relation therewith by means of rubber gaskets 19. Within the spark plug well is screwed a spark plug 21 which is in communicative relation with respect to the cylinder chamber. It is of conventional design and includes an upper stem 22 and brass head 23. An insulated wire 24 from the distributor system is held in contact with the stem. 70

An insulating material such as bakelite is 75 molded to form a hollow cover or protector 26 for the head and stem portion of the plug. Molded in the insulator is a cup shaped member 27, provided preferably with threads to mesh with those of the stem, and including 80 an enlarged portion 28 which is adapted to receive a resilient member 29 that is secured to the end of the wire. By means of this construction the wire may be pushed into the opening in the upper portion of the insulator 85 until the resilient portion is sprung within the enlargement of the cap member 26 where it is retained securely.

It will be noted that the manner of maintaining the wire in engaged relation with respect to the stem is optional, the important feature of the embodiment being the insulating member which encompasses the stem and head of the plug. It will also be noted that the invention is not limited to combinations 95 with Knight engines, but may be extended to any engine wherein the plug assumes a similar deep seated position.

Although there is described but a single embodiment of my invention, it will be ap- 100

parent to those skilled in the art that other insulating materials may be utilized and other structural details may be employed without departing from the scope of the invention,
5 and I desire therefore that it be limited only as indicated in the appended claims.

I claim:

1. The combination with the head of a Knight engine including a spark plug well, 10 of a spark plug, a wire connection thereto, a dielectric member insulating the end of the plug and the wire connected therewith, said dielectric member having a lower recess surrounding the spark plug, an upper recess 15 surrounding the wire connection coaxial with the first recess, and a restricted opening between the recesses forming a shoulder to engage the spark plug, said upper recess opening upwardly whereby the wire connection is 20 supported coaxially of the plug and in spaced relation to the well.

2. An insulator for adapting spark plugs having threaded terminals to Knight engines, comprising a body portion having recesses 25 adapted to receive the upper portion of the spark plug, a neck portion above the recess having a threaded opening adapted to screw onto the terminal, said insulator having a second recess above the neck portion adapted 30 to enclose and support a spark plug wire in co-axial alignment with the recess, said neck portion having its threaded opening extending through the same and permitting the terminal to project through the neck portion 35 into the upper recess, and means adapted to retain an electrical conductor within the second recess.

In testimony whereof, I affix my signature.
EDW. E. HUNTINGTON.
